DYNAMO-ELECTRIC MACHINE.

1,248,981.

Specification of Letters Patent. Patented Dec. 19, 1916.

Application filed May 25, 1913. Serial No. 99,754.

To all whom it may concern:

Be it known that I, AUSTIN KIMBLE, a citizen of the United States of America, and a resident of Glenellyn, county of DuPage, 5 and State of Illinois, have invented certain new and useful Improvements in Dynamo-Electric Machines, of which the following is a specification.

This invention relates to dynamo-electric machinery, and especially to alternating current motors of the compensated or inductively neutralized series conduction type, which are adapted to run on single phase circuits at variable speeds and under variable loads.

The main objects of this invention are to provide an improved form of compensating winding which forms the mounting for the armature; to provide an improved construction in which one piece performs the double function of acting as a mechanical support for the armature and acting as a short-circuited winding to compensate or neutralize armature reactions; to provide a mechanical support for the armature which also performs the part of a short-circuited winding thereby simplifying construction and reducing cost by eliminating the necessity of providing extra pole face slots and the installation of short-circuited windings therein; to provide an improved form of compensator or neutralizing member and means for applying the same to the machine; to provide an improved form of field member and means carried thereby for mounting the armature; and to provide a machine of the character described of simple construction, the parts of which are few and may be easily manufactured and assembled, 40 and may be easily interchanged or replaced.

An illustrative embodiment of this invention is shown in the accompanying drawings, in which—

Figure 1 is a rear elevation of the machine. Fig. 2 is a diagram showing the electrical connections and includes a cross section on the line A—A of Fig. 3. Fig. 3 is a horizontal section on the line B—B of Fig. 1, a top view or plan of the armature being shown. Fig. 4 is an elevation of one of the pole faces, showing the slot for the compensator frame.

In the construction shown, the machine comprises a magnetic field member or frame 1 of laminated construction having energiz-

ing windings or coils 2 thereon, and an armature 3 disposed in operative relation to and between the pole pieces 4. Said armature is carried by a rigid member or yoke 5 of open construction, the opposite sides 6 of which are mounted in the apertures or slots 7 disposed transversely in the pole faces 8 of said frame, and the opposite ends 9 of which yoke are provided with bearings 10 whereon the shaft 11 of the armature is 65 journaled.

The yoke 5 is made of non-magnetic, current-conducting material, preferably brass, constituting a closed circuit member of low impedance and large current capacity, and 70 being disposed about the armature in duly inductive relation thereto and to the pole faces 8, is peculiarly adapted to serve efficiently as a compensating member; whereby distortion of the field may be reduced to a 75 minimum and sparking at the brushes prevented.

One or more shoulders 15 are provided on the yoke 5 adapted to bear or seat against one side of the frame 1 when the device is 80 assembled, preferably adjacent to the pole faces, said shoulders being perforated and preferably threaded, as at 17, to register with and receive the end of a bolt or screw 18 passing through or engaging the frame 85 member 1, which bolt may also assist in clamping together the field laminations or plates 20. Brush holders 24 and brushes 25 are provided on said yoke adjacent to one of the bearings 10 to register with the 90 commutator 27 on the armature, said brush holders being of any desired construction adapted for the purpose, as understood in the art.

When the machine is assembled, the armature and field windings are connected in series by the lead 30, and the terminals of the machine may then be connected as by leads 33 to a source 34 of single phase alternating current, any suitable switching means 35 being provided in the line circuit for controlling the supply of power as usual for motors of this character.

The machine may be disassembled by removing the compensator-mounting screws 105 18 and then withdrawing the frame 5 with the armature journaled thereon. The armature may then be removed from the compensator frame 5 by taking out the journal fastening screws 40 fitting in the threaded 110

apertures 41. By reversing the foregoing operation the machine may be assembled.

Although but one specific embodiment of this invention is herein shown and described, it will be understood that numerous details of the construction shown may be altered or omitted without departing from the spirit of the invention as defined by the following claims.

10 I claim:

1. A compensated or inductively neutralized series conduction motor in which the compensation conductor is rigid and provided with journal bearings for supporting 15 the armature.

2. A dynamo-electric machine comprising a magnetic field member having pole faces, an armature inductively related to said field member and disposed adjacent to said pole faces, and a compensating member carried by said field member, said compensating member being of a rigid character and having journal bearings, and said armature being mounted on said bearings.

25 3. In a single phase motor, a field member having energizing windings thereon and a pair of pole faces, in combination with a rigid, closed circuit yoke having opposite sides embedded in said pole faces, and an 30 armature journaled on said yoke to operative relation to said pole faces.

4. In a single phase motor, a field member having energizing windings thereon and a pair of pole faces, in combination with a 35 rigid, closed circuit yoke having opposite sides embedded in said pole faces, an armature journaled on said yoke in operative relation to said pole faces, and a source of alternating current connected in series with 40 said windings and armature, the latter being provided with a commutator, and brushes suitably disposed on said machine for connecting the circuit to said commutator.

5. In a device of the class described, a 45 field member and an armature disposed in

operative relation to each other, in combination with a rigid, closed-circuit conductor disposed about said armature, said field member having polar faces and said conductor having its opposite sides embedded in said 50 polar faces for support, and said armature being journaled on the opposite intermediate parts of said conductor.

6. In a device of the class described, an armature and a field member having transversely slotted pole faces, in combination with means for supporting the armature on said pole faces, said means comprising a rigid member of open construction adapted to receive the armature and having bearings 60 therefor, and its sides being formed to fit slidably in the face slots of said field member for assembling the device, and means for securing the armature supporting member 65 in place.

7. In a device of the class described, a rigid compensating member of open construction having oppositely disposed sides whereon it may be supported, said member having journal bearings at its opposite ends 70 and being provided with a plurality of brush holders.

8. A device of the class described comprising a field member having polar parts thereon and an armature disposed in operative relation to said polar parts, in combination with a rigid open support member whereon the armature is journaled, said support member being slidable lengthwise (with the armature thereon) into said field member to engage said polar parts in close fitting relation for support thereby, said field and support members having coacting shoulders to limit their relative movement in one direction, and locking means to prevent withdrawal of said support member.

Signed at Chicago this 22nd day of May, 1916.

AUSTIN KIMBLE.
